(57) **CLAIM**

The ornamental design for a liquid transport device, as shown and described.

DESCRIPTION

FIG. 1 is a perspective view of a liquid transport device showing my design;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view thereof;

FIG. 8 is a perspective view wherein the liquid transport device is shown in an environmental position of use received in a housing.

FIG. 9 is an enlarged detail view of area 9 taken from FIG. 6; and,

FIG. 10 is an enlarged detail view of area 10 taken from FIG. 7.

The dot dash broken lines indicate cutoff boundaries for enlarged detailed portion views and form no part of the claim.
